(57) **CLAIM**

The ornamental design for portions of a display assembly, as shown and described.

DESCRIPTION

FIG. 1 is a perspective view of a portion of a display assembly in accordance with said design;

FIG. 2 is a top plan view of the portion of a display assembly shown in FIG. 1;

FIG. 3 is a front view of the portion of a display assembly shown in FIG. 1;

FIG. 4 is a rear view of the portion of a display assembly shown in FIG. 1;

FIG. 5 is a left side view of the portion of a display assembly shown in FIG. 1;

FIG. 6 is a right side view of the portion of a display assembly shown in FIG. 1;

FIG. 7 is a bottom plan view of the portion of a display assembly shown in FIG. 1; and,

FIG. 8 is a further perspective view of the portion of a display assembly shown in FIG. 1.

The broken lines shown in the Figures represent portions of the portions of a display assembly that are unclaimed environment, boundaries, contour lines, fold lines, or a combination thereof only, that form no part of the claimed design. The broken lines consisting of evenly sized dashes depict parts of the portions of a display assembly that form no part of the claimed design. The broken lines consisting of a dash, a dot, and a dash define the bounds of the claimed design and form no part of the claimed design. All surfaces not shown form no part of the claimed design. The shade lines in the Figures show contour and not surface ornamentation. The oblique line shading in the Figures shows a transparent surface and not surface ornamentation.
